UNITED STATES PATENT OFFICE.

GEORGE P. CARRY, OF JANEVILLE, WISCONSIN.

SEWING-MACHINE.

1,263,853.

Specification of Letters Patent. Patented Apr. 23, 1918.

Application filed December 3, 1917. Serial No. 205,191.

To all whom it may concern:

Be it known that I, GEORGE P. CARRY, a citizen of the United States, residing at Janesville, in the county of Rock and State of 5 Wisconsin, have invented certain new and useful Improvements in Sewing-Machines, of which the following is a specification.

This invention relates to sewing machines, and more particularly to a machine for sewing 10 shoes and similar purposes.

One of the main objects of the invention is to provide a machine so constructed as to permit threads of different colors to be used selectively so as to facilitate sewing shoes of 15 different colors or shades. A further object is to provide a machine having a rack for supporting a plurality of spools of thread of different colors, a needle bar being provided for receiving these threads, tensioning and take-up devices being mounted intermediate the spool rack and needle bar. A further object is to provide a needle bar having means for receiving a plurality of threads and also being provided with means 25 for releasably securing the free ends of the threads which are not being used. Further objects will appear from the detailed description.

In the drawings:

30 Figure 1 is a view in side elevation of a machine constructed in accordance with my invention.

Fig. 2 is a top plan view of the same.

Fig. 3 is a fragmentary vertical section 35 through the needle bar.

Fig. 4 is a section taken substantially on line 4—4 of Fig. 3.

Fig. 5 is a detail top plan view of the needle bar and the machine for connecting 40 the same to the take-up lever.

Fig. 6 is a section through the tensioning device.

Fig. 7 is a perspective detail of the take-up arm.

45 The machine designated generally by A is of standard construction having the upper bar B, head C, lower arm D, and presser-foot E, all as usual. A take-up lever 1 is rockably supported on the upper bar B and 50 is provided, at its forward end, with a take-up member or arm 2 which is pivotally secured in a recess in the lever by a pin 3, the inner end of the arm being cut out to provide a stop finger 4. The arm is normally 55 held in raised position by a leaf-spring 5 secured thereto at its outer end and extend-

ing into a recess in the lever 1 so as to lift member 2. The finger 4 engages the inner end of the shank 6 of a clevis 7 secured in the forward end of lever 1 so as to positively 60 limit the upward movement of member 2. The clevis is secured by pin and slot connections to a lug 8 formed integral with the needle bar 9 reciprocable through head C, by means of a pin 10 secured through the 65 arms of the clevis 7 and passed through a slot 11 in ear 8. By this construction, when the needle bar 9 is reciprocated during the sewing operation, the lever 1 and member 2 will be oscillated in the well-known manner 70 so as to take up any looseness or slack in the thread. For this purpose, member 2 is provided with a head 12 formed integral therewith provided with the three arms 13, 14, and 15 extending in spaced parallel relation 75 and each provided at its forward end with an integral thread-receiving eye 16, 17, and 18, respectively. This take-up operates in the well-known manner common to machines of this type and need not, therefore, be 80 further described in detail.

85 Adjacent the inner end of arm B is secured a spool rack 19 provided with the spaced spool posts 20, in this case 3 in number. These posts coöperate with the rack to 85 rotatably support three spools *a*, *b*, and *c* of thread of different colors as black, white, and tan. The threads from these spools are passed forwardly on arm B through suitable eyes provided for this purpose and 90 thence through a tensioning device and the take-up, being then inserted through the needle bar 9. The tensioning device is shown more clearly in Figs. 1 and 6 of the drawings. This device comprises a post 21 95 secured in head C and provided at its upper end with a knurled flange 22, sheet metal disks 23, 24, 25, and 26 mounted about the post so as to be slidable thereon, and a coil tension spring 27 mounted about the post 100 and confined between the flange 22 and the uppermost disk 26. The spring acts to resiliently force the disks together, and the threads from the spools *a*, *b*, and *c* are passed between the successive pairs of disks 105 so as to be gripped frictionally thereby thus tensioning the thread in the well-known manner. The lower portion of post 21 is threaded, as at 21^a, so that the effective strength of spring 27 may be varied by 110 screwing the post into or out of the head as is common practice in devices of this sort.

After the threads from the spools have been inserted through the take-up member 2, they are then led downward through the needle bar 9. For this purpose bar 9 is provided with three spaced bores 28, 29, and 30 extending the full length thereof. The bar is further provided, in its lower end portion, with an axial bore 31 for receiving the needle which is secured therein by a set screw 32. In using this machine, but one thread is inserted into the needle at a time, the loose ends of the other two threads being drawn up about the lower end of the needle bar 9 and frictionally secured by being inserted between a spring clip 33 fitting snugly about bar 9 a short distance above the lower end thereof and detachably secured to the bar by a screw 34, the free end of this spring being turned out slightly, as at 35, to facilitate insertion of the threads between the same and the bar. By this arrangement, it is possible to quickly and easily change the color of the thread being used to correspond with the color of the shoe or other piece of work being operated upon, without the necessity of completely rethreading the machine. For instance—assuming that the spool A carries black thread, B white thread, and C tan thread, and the sewing of a black shoe has been completed and it is desired to sew a tan shoe: In this case, the thread a^1 from spool A which is passed through bore 30 of bar 9 and threaded through the needle 36 will be withdrawn from the needle and inserted between the spring 33 and bar 9, after which the tan thread c^1 from spool C which is inserted through bore 28 of the bar, will be released from spring 33 and inserted through the eye of needle 36. When this has been done, the machine is threaded with tan thread and may be used for sewing the tan shoe. This renders it possible to quickly and easily change from one color of thread to another so as to accommodate the color of shoe being operated upon without necessitating the complete rethreading of the machine as is now done, thus effecting a material saving in work and time.

It will be evident that there may be slight changes made in the construction and arrangement of the details of my invention without departing from the field and scope of the same, and I intend to include all such variations, as fall within the scope of the appended claims, in this application in which a preferred form only of my invention is disclosed.

What I claim is:

1. In sewing machines, a rack adapted to support a plurality of spools of thread, tension devices for receiving threads from spools mounted on said rack, a rockable take-up lever, a take-up member carried thereby and provided with a plurality of

spaced arms having eyes for receiving threads from said tension devices, a reciprocable needle bar adapted to receive threads from said take-up member, and connections between the needle bar and the take-up lever for oscillating said lever when the bar is reciprocated.

2. In sewing machines, a rack adapted to support a plurality of spools of thread, tension devices for receiving threads from spools mounted on said rack, a rockable take-up lever, a take-up member carried thereby and provided with a plurality of spaced arms having eyes for receiving threads from said tension devices, a reciprocable needle bar having longitudinally extending bores for receiving threads from said take-up member, and connections between the needle bar and the take-up lever for oscillating said lever when the bar is reciprocated.

3. In sewing machines, a rack adapted to support a plurality of spools of thread, tension devices for receiving threads from spools mounted on said rack, a rockable take-up lever, a take-up member carried thereby and provided with a plurality of spaced arms having eyes for receiving threads from said tension devices, a reciprocable needle bar having longitudinally extending bores for receiving threads from said take-up member, and connections between the needle bar and the take-up lever for oscillating said lever when the bar is reciprocated, and means for releasably securing the free ends of said threads.

4. In sewing machines, a rack adapted to support a plurality of spools of thread, tension devices for receiving threads from spools mounted on said rack, a rockable take-up lever, a take-up member carried thereby and provided with a plurality of spaced arms having eyes for receiving threads from said tension devices, a reciprocable needle bar having longitudinally extending bores for receiving threads from said take-up member, connections between the needle bar and the take-up lever for oscillating said lever when the bar is reciprocated, and means carried by the said needle bar for releasably securing the free ends of said threads.

5. In a sewing machine, a rack adapted to support a plurality of spools of thread, tension devices for receiving threads from spools mounted on said rack, a rockable take-up lever on the upper bar of the machine, a take-up member carried thereby and provided with a plurality of spaced arms having eyes for receiving threads from said tension devices, a needle bar reciprocably mounted through the head of the machine and provided with spaced bores extending the full length thereof for receiving threads from said take-up member,

means for oscillating the take-up lever when the needle bar is reciprocated, and a securing spring mounted on the needle bar adjacent the lower end thereof and fitting snugly about the same so as to releasably secure the free ends of threads passed through the needle bar.

Copies of this patent may be obtained for five cents each, by addressing the "Commissioner of Patents, Washington, D. C."

In testimony whereof I affix my signature in presence of two witnesses.

GEORGE P. CARRY.
